VALVE MECHANISM

William M. Scott, Jr., Bryn Mawr, Pa., assignor to
 I. T. E. Circuit Breaker Company, Philadelphia,
 Pa., a company of Pennsylvania

Application March 4, 1943, Serial No. 477,911,
 now Patent No. 2,426,243, dated August 26,
 1947, which is a division of application Serial
 No. 373,051, January 3, 1941, now Patent No.
 2,405,454, dated August 6, 1946. Divided and
 this application November 24, 1943, Serial No.
 511,536

3 Claims. (Cl. 137—144)

1

My invention relates in general to the field of circuit interrupters and more specifically concerns a novel and improved form circuit breaker and a control means therefor. This case is a division of my application Serial No. 477,911, filed March 4, 1943, which is a division of the parent application Serial No. 373,051, filed January 3, 1941, now Patent Number 2,405,454, granted August 6, 1946, and entitled Circuit interrupter and control therefor. The present invention embodies a novel high speed valve mechanism for controlling the application of pressure to the pneumatically operated circuit breakers such as described in the above referred to parent application.

Accordingly an object of this invention is to provide a novel high speed valve mechanism in which a pair of diaphragms cooperate with a valve member, the diaphragms being operated by pressure from a source of compressed fluid, a spring member, and aspirating means.

There are other objects of the invention which will become apparent from the detailed description of the drawings, in which:

Figure 1 is a cross-sectional view of the pneumatic operating means in the position corresponding to the circuit breaker open circuit position.

Figure 2 is a cross-sectional view of the pneumatic operating means corresponding to the circuit breaker closed position.

Figure 3 is an end cross-sectional view of the pneumatic operating means taken along the line 14—14 of Figure 2. As described in the above referred to parent application, pneumatically operated circuit breakers are operated by compressed air. This air is delivered to the circuit breakers over pipe 22.

The control valve which is most clearly illustrated in Figures 1, 2 and 3 is operated by a pair of oppositely disposed solenoids; that is, trip solenoid 302 and closing solenoid 303.

Compressed air from the storage means enters the control valve through pipe 304 and flows to and from the operating cylinder through the manifold 32. These pipes 304 and 22 are secured to the valve by means of a block 306 suitably perforated which, in turn, is supported upon the main circuit breaker frame.

The control valve comprises a cylindrical body portion 307 which is secured to the block 306 by a plurality of bolts 297 which pass through corresponding lugs 295 on either side of the block 306 and the cylindrical body 307 respectively. A gasket 311 is interposed between these members to prevent air leakage thereat.

2

The cylindrical member 307 is cored to produce annular air chambers 312 and 313 which are separated by means of an integrally cast partition 314. Supported upon the partition is another hollow cylindrical member 315 which is bored out to afford a passage 316 between the two annular chambers 312 and 313.

Operable within the cylinder 316 is a spool-shaped member 317 which essentially comprises a central portion of narrow diameter and two pistons 321 and 322 which are operable along the inner surface thereof.

The end 323 of the inner cylindrical member is of smaller diameter than the opposite end 15 thereof in order to provide an abutment 324 for a compression spring 325 which constantly exerts a force on piston 321 towards the left as viewed in Figure 1 and Figure 2.

Adjacent the pistons, as indicated more particularly in Figure 3, are star-shaped elements 331 and 332 as indicated in Figure 3, which maintain alignment when the pistons are displaced beyond the ends of the passage; while permitting air to flow therethrough.

25 The open ends of the main cylindrical member 307 are sealed by a pair of flexible diaphragm valves 337 and 336 firmly secured thereto by a corresponding pair of dome shaped circular members 333 and 334, fastened to the main structure by any suitable means as for example screws 335.

The diaphragm 336 is free of the piston 321 whereas the diaphragm 337 is attached by means of screws 341 and metal plate 342 to the piston 322. In addition, piston 322 also carries a cylindrical member 343 which is faced with a layer of valve seat material 344.

This cylindrical member 343 is preferably fixed to a rod 345 which is slidable within a corresponding perforation 346 within the piston 322 and is constantly biased from the diaphragm 337 by means of leaf spring 347 which accordingly serves as a shock absorber during closures of valve 344, as will be described.

45 As illustrated in Figures 1 and 2, the circuit breaker closing manifold 22 enters into the cylinder 316 which is supported by partition 314. Air is exhausted from the control valve through annular passage 313 and the exhaust pipe 335 connected thereto.

The air in annular passage 312 is at the pressure of the supply system, and thus the left face of diaphragm 337 is acted upon by a corresponding force.

However, as illustrated, a small passage 352 50 interconnects the space 355 formed by the dome

334 and the annular chamber 312, thus equalizing the unit pressures on the faces of diaphragm 337.

Since the high pressure air in annular space 312 acts upon an annular area whereas high pressure air within the space 333 acts upon a full circular area of equal outer diameter, the diaphragm valve 337 is displaced to the left (the maximum displacement being indicated in Figure 1). The spring 325, as may also be seen, acting upon the spool shaped member 317, adds to the force which draws diaphragm 337 in this direction.

When the valve diaphragms are in the position indicated, the circuit breaker operating cylinders (not shown) are vented through insulating pipe 301 and through pipe 22 which leads to the cylindrical passage 316. The air is then free to flow from this passage through the star-shaped element 332 into the annular passage 313 and thus to the atmosphere through the exhaust pipe 351.

Pressures on the opposite faces of diaphragm 336 are equalized through small passage 354 which interconnects the manifold 22 and the dome shaped space 355.

Fine strainers are preferably introduced into the auxiliary equalizing passages 352 and 354 to preclude the entry into the dome of dust or other foreign particles which would cause faulty seating of the valves.

The dome-shaped elements 333 and 334 are centrally perforated at 361 and 362 respectively to form a pair of auxiliary valves which may be sealed by solenoid plungers 365 and 366 surfaced with layers of valve seat material 363 and 364 respectively. These plungers are spring compressed toward their respective valves by compression springs 367 and 371 which are retained within axial recesses in the plunger and in the solenoid stops 369 and 370. The force exerted by the springs must be sufficient to ensure effective valve closures when full supply pressure exists within the dome shaped spaces. Manual operation of the plungers is provided for by plunger rods 372 and 373 tapped into their corresponding plungers and which pass through appropriate centralizing bushings in the solenoid steps.

The coil solenoids 302 and 303 are preferably energized from a control circuit hereinafter described and are supported upon the main valve structure by means of the posts 381.

Control valve operation

As previously mentioned, when the valve members are as illustrated in Figure 1, the circuit breaker contacts are open and the manifold 22 is vented through exhaust pipe 351 to the atmosphere.

If the closing solenoid 303 is energized or if the plunger rod 373 is actuated so that the plunger 366 is drawn in against the action of compression spring 371 and bears against its corresponding stop 370, then the passage 362 will vent the dome shaped space 334 to the atmosphere.

Inasmuch as the equalizing air flow through relatively small passage 352 is less than the air flow to the atmosphere through the larger passage 362, the high pressure air within chamber 312 will act to displace diaphragm 337 toward the right when viewed as in Figure 1.

The displacement of diaphragm 337 will accordingly cause the displacement of the attached spool-shaped member 317 and thus piston 322 will move beyond the open end 323 of cylindrical member 313 and permit the high pressure air

to enter the circuit breaker manifold through the star-shaped member 331 as is more particularly illustrated in Figure 2.

Piston 321 will, by virtue of the displacement of the entire member 317, enter the cylinder 315 and block the flow of air from the manifold to the atmosphere through pipe 351.

The increase in pressure within manifold 22 will cause a corresponding increase in pressure in the space 355 due to the equalizing passage 354. Since the right hand face of this diaphragm is obviously at atmospheric pressure, this increase in pressure will act to force and maintain flexible diaphragm 336 against its seat 382 and thus effectively seal the passage 316.

Thus actuation of plunger 366, as hereinabove mentioned, will cause the various operating members to assume the positions illustrated in Figure 2, wherein as indicated by the air flow arrowheads, compressed air from the supply passes through the star-shaped member 331 and enters the circuit breaker manifold 22 and thus causes contact engagement.

The cylindrical member 343 and its associated valve seat 344 will act subsequent to displacement to seal passage 362 against the escape of high pressure air. Subsequent to circuit breaker closure, there will be no tendency for the spool shaped member to return to the position indicated in Figure 1, since the combined forces of the high pressure air acting upon the left surfaces of the diaphragms is substantially greater than the combined forces of the compression spring 325 and the air acting on the right surface of diaphragm 337.

The closing solenoid plunger 366 may be permitted to return to the position indicated in Figure 1 to minimize air leakage through passage 362.

The diaphragm 337 as illustrated in Figure 2 is maintained in a position clear of its seat and thus permits air flow through star-shaped member 331 to compensate for any leakage within the various elements, as for instance, the circuit breaker closing cylinders.

Energization of the trip solenoid 302, or manual actuation of rod 372 to cause the displacement of plunger 365 to the left as viewed in Figures 1 and 2, will accordingly permit air passage 361 to vent the high pressure air contained within the dome 355 to the atmosphere.

The venting action will occur at a more rapid rate than the flow of equalizing air from the high pressure manifold through passage 354 and thus the diaphragm 336 will tend to move towards its neutral position.

Therefore, under the influence of spring 325 and the high pressure air, the spool shaped member 317 will correspondingly be displaced and thus 60 will pull the diaphragm 337 against its seat to preclude the further flow of air to the manifold.

This motion of the diaphragm is accelerated by the drop in pressure in the central cylinder 316 which occurs as soon as the air therein exhausts to the atmosphere and the leading edge of piston 322 enters its cylinder.

Thus the control valve members will again assume the position indicated in Figure 1, vent the manifold, and open the circuit breaker contacts.

Following circuit interruption, the plunger 365 may be allowed to close passage 361 as is required for a succeeding circuit closure.

Since various modifications of the hereinabove described control system will be evident to those skilled in the art, I prefer to be bound, not

by these specific disclosures, but by the scope of the appended claims.

I claim:

1. In a valve system having a first line containing a source of high pressure fluid; a second line; a pair of flexible diaphragms; valve mechanism individual to and controlled by each of said diaphragms; the valve of said first diaphragm controlling the flow of fluid from said first line to said second line; means for applying pressure from said high pressure fluid source to both faces of said first diaphragm; said first diaphragm being operable to open and close said valve under the action of said fluid pressure; spring means operating on said first valve urging it into position for disconnecting said first line from said second line; and means for venting one side of said first diaphragm whereby said diaphragm is operated by the pressure of said fluid in said first line on the face of said diaphragm acting against said spring means to connect said first and second line; a passage means for venting said second line to the atmosphere and means for operating said second diaphragm under the action of pressure in said second line into position closing said venting passage of said second line to the atmosphere.

2. In a valve structure, a first line; a second line; a flexible diaphragm operated valve having a connecting position for connecting said first and second lines and a disconnecting position for disconnecting said first line from said second line, both faces of said diaphragm being under equal pressure in both its connecting and disconnecting positions; spring means normally urging and holding said diaphragm valve to its disconnecting position; means for venting one side of said diaphragm valve to cause a drop of pressure on said one side, said diaphragm valve being thereupon operable by the pressure on its other side for operation to the position for connecting said first and second lines; and means controlled by pressure in said second line for maintaining said diaphragm in valve connecting position against the action of said spring means; said means comprising a second flexible diaphragm controlled by pressure in said second line.

3. In a valve structure, a first line; a second line; a flexible diaphragm operated valve having

a connecting position for connecting said first and second lines and a disconnecting position for disconnecting said first line from said second line, both faces of said diaphragm being under equal pressure in both its connecting and disconnecting positions; spring means normally urging and holding said diaphragm valve to its disconnecting position; means for venting one side of said diaphragm valve to cause a drop of pressure on said one side, said diaphragm valve being thereupon operable by the pressure on its other side for operation to the position for connecting said first and second lines; means controlled by pressure in said second line for maintaining said diaphragm in valve connecting position against the action of said spring means; said means comprising a second flexible diaphragm normally disconnected from and brought into operating engagement with said first diaphragm under contrast of the pressure in said second line; means for applying equalized pressure on both faces of said second diaphragm; and means for venting one face of said second diaphragm to permit the pressure in the other face of said second diaphragm to operate said second diaphragm whereby said spring means operates said first diaphragm and its valve to disconnected position.
